(57) **CLAIM**

The ornamental design for a tree-shaped ornament display rack, as shown and described.

DESCRIPTION

FIG. 1 is a perspective view of a first embodiment of the rack with open branching, a base, and pegs shown in dashed lines as they are not a part of the design.;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof; and,

FIG. 8 is a perspective view of a second embodiment of the rack with closed branching, no base, and hooks shown in dashed lines as they are not a part of the design.
